UNITED STATES PATENT OFFICE

168,262

PLATE OR SIMILAR ARTICLE

Hans Hacker, East Liverpool, Ohio, assignor to
The Walker China Company, Bedford, Ohio

Application August 19, 1952, Serial No. 21,109

Term of patent 14 years

(Cl. D44—15)

To all whom it may concern:

Be it known that I, Hans Hacker, a citizen of no country, residing at East Liverpool, county of Columbiana, and State of Ohio, have invented a new, original, and ornamental Design for a Plate or Similar Article, of which the following is a specification, reference being had to the accompanying drawing, forming part thereof, wherein,

The figure on the drawing is a plan view of a plate of a conventional configuration showing my new design.

The dominant feature of my design resides in the ornamentation around the periphery of the plate as shown.

I claim:

The ornamental design for a plate or similar article, substantially as shown and described.

HANS HACKER.
